Patented Apr. 19, 1921.

FIG. 1.

FIG. 3.

FIG. 4.

FIG. 2.

Inventor :

William S. MacLeewe

By his Attorney

F. Bellitt Goodwin

UNITED STATES PATENT OFFICE.

WILLIAM S. MACLEWEE, OF TRENTON, NEW JERSEY, ASSIGNOR TO CARRIE HOWELL
MACLEWEE, OF TRENTON, NEW JERSEY.

LAMP-ADJUSTER.

1,375,224.

Specification of Letters Patent. Patented Apr. 19, 1921.

Application filed October 25, 1918. Serial No. 259,646.

To all whom it may concern:

Be it known that I, WILLIAM S. MACLEWEE, a citizen of the United States, residing at Trenton, in the county of Mercer and 5 State of New Jersey, have invented certain new and useful Improvements in Lamp-Adjusters, of which the following is a specification.

My invention relates to improvements in 10 an adjuster for electric lamps and particularly electric lamps suspended by a flexible cord. The object of my invention is to provide an adjusting device by which the lamp may be readily raised and lowered and held 15 at any desired height; a further object of my invention is to provide means whereby the lamp shade may be held with its axis vertical or at an oblique angle, to direct the rays of light from the lamp downwardly or 20 at an angle, and a still further object of my invention is to provide an adjustable friction sleeve upon the cord, having two enlarged members detachably secured together to permit an endless ring to be loosely 25 mounted upon said sleeve and retained thereon.

Referring to the accompanying drawing;

Figure 1, is a side elevation of an electric lamp and shade showing the lamp suspended 30 by my improved adjusting device;

Fig. 2, is a view similar to Fig. 1, showing the lamp and shade suspended at an oblique angle;

Fig. 3, is a central section of one member 35 of the cord sleeve;

Fig. 4, is a view similar to Fig. 3, showing the other member of the cord sleeve.

In the drawings, in which like reference characters refer to like parts, 1 represents 40 an incandescent electric lamp socket, having attached thereto the flexible cord 2 containing the feed wires for the lamp 4. The upper end 3 of the cord 2 is attached to a fixture from which it is suspended. A shade 45 5 is secured in the lamp socket 1, in any suitable manner.

A friction sleeve 6 is mounted upon the cord 2 and is slidable thereon by hand, but fits tightly upon the cord and when inclined 50 at an oblique angle with the vertical portion of the cord it will bind upon the cord with sufficient friction to support the weight of

the lamp. The sleeve 6 is made in two parts 7 and 8 which are detachably secured together by a screw threaded extension 9 upon 55 one of the members which fits into a threaded recess 10 formed in the opposite member. Said members 7 and 8 are approximately spherical, thus forming, when joined together a reduced portion between them in 60 which is loosely mounted a ring 12, of smaller interior diameter than the spherical members, so that it cannot slip over the latter. The purpose of making the sleeve in two sections is to allow the ring to be readily 65 attached thereto and thus avoiding the necessity of using a split ring which would spring open due to the weight of the lamp.

The ring 12 carries two flexible members, in the form of chains 14 and 15, of different 70 lengths, and the chains are provided with hooks 16 and 17 secured to the lower ends thereof.

The hook 16 on the chain 14 may be inserted in the eye 20 of a plate 21 which is 75 secured upon the lamp socket 1 and the lamp will be supported by the chain 14 and suspended in a vertical position, as shown in Fig. 1. By moving the sleeve 6 to different positions upon the cord the lamp may be 80 readily raised or lowered.

By attaching the hook 17 on the longer chain 15 to the lower edge of the shade 5, the lamp may be held at an oblique angle, as shown in Fig. 2 and when in this position 85 the lamp may be raised and lowered by the adjustment of the sleeve 6 upon the cord 2.

Having thus described my invention I claim and desire to secure by Letters Patent:

An electric lamp or the like, a flexible 90 conductor attached thereto, a sleeve adapted to be mounted on the said conductor, said sleeve consisting of two spherical members, one of said spherical members having a screw-threaded projection thereon, the other 95 one of said spherical members having a screw-threaded recess formed therein adapted to receive the said projection on the first mentioned spherical member, a ring loosely mounted between the said spherical members and means carried by the said ring for holding the lamp in various positions.

In testimony whereof I affix my signature.

WILLIAM S. MACLEWEE.
